CLAIM

The ornamental design for a control handle for a materials handling vehicle, as shown and described.

DESCRIPTION

FIG. 1 is a perspective view showing the control handle of our new design mounted generally horizontally an operator's compartment of a materials handling vehicle; FIG. 2 is a front view of our new design, as viewed by an operator;

FIG. 3 is a top view of our new design;

FIG. 4 is a back view of the control handle of our design;

FIG. 5 is a right side view of the control handle of our new design; and,

FIG. 6 is a bottom view of the control handle of our new design.

The broken line showing is for illustrative purposes only and forms no part of the claimed design.

UNITED STATES PATENT AND TRADEMARK OFFICE
CERTIFICATE OF CORRECTION

PATENT NO : Des. 405,581

DATED : February 9, 1999

INVENTOR(S) : Robert J. Henshaw et al.

It is certified that error appears in the above-identified patent and that said Letters Patent is hereby corrected as shown below:

On the title page, under item [57] description,

line 2 In Fig. 1, patent reads "horizontally an operator's"
and should read - - horizontally in an operator's - - .

Signed and Sealed this

Twenty-second Day of June, 1999

Attest:

Q. TODD DICKINSON

Attesting Officer

Acting Commissioner of Patents and Trademarks
